FOUNDATION GARMENT OR THE LIKE

Philip H. Robbins, New York, N. Y., assignor to
Poirette Corsets, Inc., New York, N. Y.

Application March 29, 1938, Serial No. 198,775

11 Claims. (Cl. 2—37)

This invention relates to a foundation garment for women's wear.

A garment, in accordance with this invention is in the form of a girdle-like structure comprising an upper portion for encompassing the wearer's body at the waist and above the latter to near the busts and a lower portion for encompassing the hips, thighs, abdomen, lower portion of the back and buttocks and said type of garment is termed by the trade a foundation garment, or it may be the form aforesaid having attached to its upper end a brassière. The invention aims to provide, in a manner as hereinafter set forth, a foundation garment including a fashioned elastic body part having secured directly thereagainst sets of spaced elastic tapes for increasing the resistance of the portion of said body part to which they are secured and acting as additional fashioning for the garment.

The invention also aims to provide, in a manner as hereinafter set forth, a foundation garment including a fashioned elastic body part having secured directly against the upper portions of the sides thereof spaced elastic strips disposed in a manner to act as additional fashioning for the garment.

The invention further aims to provide, in a manner as hereinafter set forth, a foundation garment including a fashioned body having elastic spaced means at the sides of the waist portion thereof for giving additional restraining and controlling power to the garment.

The invention further aims to provide, in a manner as hereinafter set forth, a foundation garment including elastic sides having attached thereto elastic strips extending from the front and to the back of the garment for giving a waist line effect, as well as for controlling the abdomen and side back.

The invention further aims to provide, in a manner as hereinafter set forth, a foundation garment with means which are so constructed and arranged that when the garment is worn it will control the diaphragm, waist-line and the abdomen, as well as the fatty tissues of the side back muscle of the hip, resulting in the garment being held firmly in place and preventing it from riding up on the body of the wearer.

The invention further aims to provide, in a manner as hereinafter set forth, a foundation garment with means which are so constructed and arranged that when the garment is worn it tends to correct the figure of the wearer as to posture, giving the wearer firm control through the abdomen and side back portion of the hip.

without the aid of material reinforcements or boning in that particular position, as well as controlling the posture position when sitting and standing.

The invention further aims to provide, in a manner as hereinafter set forth, a foundation garment including means which are so constructed and arranged that they act as an aid to a wearer's health by holding the muscles of the abdomen more firmly and rigidly in both the standing and the sitting positions without the need for the aid of an inner belt arrangement and which further automatically tends to hold the muscles of the abdomen from sagging.

The invention further aims to provide, in a manner as hereinafter set forth, a foundation garment with means which are so constructed and arranged that when the garment is worn, they tend to hold the fatty tissue and muscle of the hip in a firm position in such a way that it will oftentimes reduce that fatty tissue, hold it firm to that portion of the body and help to relieve fatigue.

The invention further aims to provide, in a manner as hereinafter set forth, a garment which is simple in its construction and arrangement, strong, durable, compact, thoroughly efficient for the purpose intended thereby, readily assembled, pleasing in appearance and comparatively inexpensive to manufacture.

To the above ends essentially and to others which may hereinafter appear the invention consists of the novel construction, combination and arrangement of parts as will be more specifically described and illustrated in the accompanying drawings, wherein are shown embodiments of the invention, but it is to be understood that changes, variations and modifications may be resorted to which fall within the scope of the invention as claimed.

In the drawings:

Figure 1 is a front elevation of a garment, in accordance with this invention of the girdle type.

Figure 2 is a rear elevation thereof,

Figure 3 is an elevation of the garment turned inside out, looking towards the inner face of the front thereof,

Figure 4 is an elevation of the garment turned inside out looking towards the inner face of the back thereof,

Figure 5 is a sectional plan of substantially one-half of the garment,

Figure 6 is a fragmentary view in elevation looking towards the inner face of one side of the garment,

Figure 7 is a section on line 7—7, Figure 6.

Figure 8 is a fragmentary view in elevation of a modified form of garment of the girdle type looking towards the inner face of one side thereof,

5 Figure 9 is a section on line 9—9, Figure 8.

Figure 10 is a side elevation, broken away of a garment of the combination type in accordance with this invention,

10 Figure 11 is a side elevation illustrating another modified form of combination garment, in accordance with this invention and with the garment turned inside out,

Figure 12 is a section on line 12—12, Figure 10,

15 Figure 13 is a fragmentary view in side elevation of another modified form of combination garment looking towards the inner face of one side thereof, and

Figure 14 is a section on line 14—14, Figure 13.

The garment 10 as shown will be in the form 20 of an endless girdle-like body part having a slit 11 in the upper portion of its back, a soft bendable flap 12 secured to the inner face of the back and extending across the slit and closing means 13 of known form for the slit.

25 The garment 10 will be of a size to cover, with respect to the body of the wearer, the lower portion of the back, the waist, the front from the waist to the bust, the buttocks, the hips, the thighs and the abdomen.

30 The garment 10 includes a front 14, a back 15, a pair of sides 16, 17. The garment is built up from a foundation formed from a pair of oppositely disposed, fashioned, spaced webs 18, 19 of elastic woven material of the desired length and 35 which, when the garment is worn, are disposed on their lower lengthwise edges. Each web is folded inwardly upon itself. When the webs are in foundation forming position, the ends of one web align in spaced relation with respect to the 40 ends of the other web. Each web has secured to its upper and lower lengthwise edges respectively, upstanding and depending elastic straps 20, 21 extending from one end to the other end of the web. Each web and the upper elastic strap 45 associated therewith has secured thereto concealed flexible stay means positioned on the vertical medians of the strap and web. The stay means extend from the upper edge of an upper strap substantially to the lengthwise median of the web. The stay means slightly inclines rearwardly from its outer to its inner end. The said stay means secured to the straps 20 and webs 18, 19 are positioned substantially on the vertical centers of the upper portions of the sides 16, 17 50 of the garment. The said stay means are indicated at 22, 22a.

The garment 10 includes a non-elastic front portion or part 23 of a length to extend from the outer lengthwise edges of the straps 20 to 60 the outer lengthwise edges of the straps 21. The front portion 23 has fixedly secured therein and lengthwise thereof a pair of spaced parallel flexible stay members 24, each located adjacent a side of the lengthwise median of the front piece. 65 The stay members 24 extend from the top of the front portion to a point below the transverse median of the latter.

The front ends of the straps 20 extend into and are secured to the upper parts of the sides 70 of the front portion. The outer lengthwise edges of the straps 20 substantially align with the top edge of the front portion. The front ends of the straps 21 extend into and are secured to the lower parts of the sides of the front portion. The 75 outer lengthwise edges of the straps 21 substan-

tially align with the bottom edge of the front portion. The front ends of the webs 18, 19 extend into and are secured to the intermediate parts of the sides of the front portion.

The garment 10 includes a non-elastic back portion or part 25 of a length to extend from the outer lengthwise edges of the straps 20 to the outer lengthwise edges of the straps 21. The back piece 25 is of greater width than the front piece 23. The back portion 25, centrally of its upper part is slotted and which provides the slit 11. The flap 12 is secured at one side to the inner face of the back portion 25 adjacent one of the edges of the slit. The back portion 25 has arranged therein and secured thereto a pair of spaced parallel stay members 26 which extend from its upper end to a point in proximity to its lower end. The members 26 are arranged on opposite sides of the slit. Below the latter the back portion has a stay means 26a.

20 The rear ends of the straps 20 extend into and are secured to the upper parts of the sides of the back portion 25. The outer lengthwise edges of the straps 20 substantially align with the top edge of back portion 25. The rear ends 25 of the straps 21 extend into and are secured to the lower parts of the sides of the back portion 25. The outer lengthwise edges of the straps 21 are substantially aligned with the bottom edge of the back portion. The rear ends of the 30 webs 18, 19 are secured to the intermediate parts of the sides of the back portion 25.

The garment 10 includes four sets of elastic members of tape-like form. The sets are arranged in pairs. Each pair consisting of a front 35 set and a rear set. The members of one set of a pair are oppositely disposed with respect to the members of the other set of the pair. The number of members of a set may be as desired, preferably three and are so shown. The members of 40 one pair of sets are arranged in relation in the same manner as the members of the other set of the pair, but are oppositely disposed. The members of one front set are indicated at 27, 28, 29, those of the other front set at 30, 31, 32, those 45 of one rear set at 33, 34, 35 and those of the other rear set at 36, 37, 38. The members 27, 28, 29 are oppositely disposed with respect to the members 30, 31, 32. The members 33, 34, 35 are oppositely disposed with respect to the members 36, 37, 38. 50 The members 27, 28, 29 are oppositely disposed with respect to the members 33, 34, 35. The members 30, 31, 32 are oppositely disposed with respect to the members 36, 37, 38. The said several sets of members are secured to the inner faces of the webs 18, 19 and the manner in which the sets of a pair are disposed relative to each other, as well as the arrangement of the members of each set of the a pair of sets are shown in 55 Figure 6. The member 28 is disposed between the members 27, 29. The member 31 is disposed between the members 30, 32. The member 34 is arranged between the members 33, 35 and the member 37 is arranged between the members 36, 38. The members of the front sets align with 60 each other. The members of the rear sets align with each other.

The members 27, 28, 29 at there front ends extend into and are secured to one side of the front portion 23 and at their rear ends extend into and 65 are secured to one side of the stay means 22. The rear ends of the members 27, 28, 29 are arranged in closed relation. The member 28 is horizontally disposed. The members 27, 29 from their rear ends extend at opposite inclinations 75

throughout to dispose them diagonally relative to a web and whereby the spaces between member 28 and members 27, 29 gradually increase in width in a forward direction. The member 27 extends at an upward inclination from its rear end and the member 29 at a downward inclination from its rear end. The members 30, 31, 32 at their front ends extend into and secured to the other side of the stay means 22 and at their rear ends extend into and are secured to one side of the back portion 25. The front ends of the members 30, 31, 32 are arranged in close relation. The member 31 is horizontally disposed. The members 30, 32 from their front ends extend at opposite inclinations throughout to dispose them diagonally with respect to a web and whereby the spaces between member 31 and members 30, 32 gradually increase in width in a rearward direction. The member 30 extends at an upward inclination from its front end, and the member 32 at a downward inclination from its front end. The members 33, 34, 35 at their front ends extend into and are secured to the other side of the front portion 23 and at their rear ends extend into and are secured to one side of the stay means 22^a. The rear ends of the members 33, 34, 35 are arranged in close relation. The member 34 is horizontally disposed. The members 33, 35 from their rear ends extend at opposite inclinations throughout to diagonally dispose them with respect to a web and whereby the spaces between member 34 and the members 33, 35 gradually increases in width in a forward direction. The member 33 extends at an upward inclination from its rear end, and the member 35 at a downward inclination from the rear end. The members 36, 37, 38 at their front ends extend into and are secured to the other side of the stay means 22^a and at their rear ends extend into and are secured to the other side of the back portion 25. The front ends of the members 36, 37, 38 are arranged in close relation. The member 37 is horizontally disposed. The members 36, 38 from their front ends extend at opposite inclinations throughout to dispose them diagonally with respect to a web and whereby the spaces between member 37 and members 36, 38 gradually increase in width in a rearward direction. The member 36 extends at an upward inclination from its front end and the member 38 extends at a downward inclination from its front end.

The front end terminal portions of the members 27, 33 extend to the front ends of the straps 20. The rear end terminal portions of the members 30, 36 extend to the rear ends of the straps 20. The front ends of the members 27, 33 are positioned near the upper end of the front portion 23. The front ends of the members 29, 35 are arranged at the transverse median of the front portion 23. The rear ends of the members 30, 36 are positioned near the top of the back portion 25. The rear ends of the members 32, 35 are arranged at the transverse median of back portion 25.

The top and bottom edges of the members of the said sets are secured throughout to the webs 18, 19 by zig-zag stitching 39. The ends of the members of the said sets are secured to the stay means 22, 22^a, front and back portions 23, 25 by suitable stitching. The elastic straps are secured to the webs 18, 19 by suitable stitching. The concealing means for the stay means 22, 22^a are secured to the webs 18, 19 by suitable stitching. The front and back portions are secured to the webs and elastic straps by suitable stitching

which also acts to secure the members of the sets to said front and back portions.

The garment may be provided with hose supports and is so shown. The said supporters are indicated at 40.

The members of the said sets preferably are secured to the inner faces of the webs and are so shown, but it is to be understood that they may be secured to the outer faces of the webs. The members are of uniform width, but the length of the members 28, 31, 34, 37 is less than the length of the others of the said members. The members 28, 31, 24, 37 are of like length and the others of the said members are of like length.

The members of the said sets constitute means for increasing the resistance at spaced portions of the garment, as will act as an additional fashioning and coat with the other elastic parts of the garment for obtaining the objects and advantages of the invention.

With reference to the modified form shown by Figures 8, 9 the difference between the form shown thereby resides solely in the widths of the elastic members of each set. In Figure 8 a pair of oppositely disposed sets of elastic members are shown. The members of one set are indicated at 41, 42, 43 and those of the other set at 44, 45, 46. One end of each of the members of each of the sets is secured to a finishing strip 30 or stay means 47 extending from the top to the bottom and centrally of the sides of the garment. The other ends of the members 41, 42, 43 are secured to one side of the front portion 48. The other ends of the members 44, 45, 46 are secured to one side of the back portion 49. The members 41, 44 are of like width, but of less width than the members 42, 43, 45, 46. The members 43, 46 are of greater width than the members 42, 45. Otherwise than that as stated by Figures 8 and 9 will be the same as the garment 10.

With reference to Figure 10 the garment 51 shown thereby is of the combination type, that is to say it consists of a lace brassière 52 and a corset 53. The latter constitutes the body part of garment 51. Each side of the garment 51 is formed centrally thereof with a non-elastic fabric strip or stay means extending from the top edge to the bottom edge of the corset 53. The strips are indicated at 54, 55. One side of the brassière is slitted, as at 55^a and such side carries a closure means 56 of known form for the slit. Each side of garment 51 includes an upper part 57 formed by a side of the brassière and a pair of oppositely disposed lower parts in the form of fashioned, spaced webs 59, 60 of elastic woven fabric. The corset includes a non-elastic front portion and a non-elastic back portion 61, 62 respectively. The top edge of said front portion 61 is arranged above the top edge of the back portion 62. The sides 57 of the brassière depend between the side edges of the front portion 61 and the back portion 62 to the top edges of the webs 59 and strips 54, 55. Each side of the garment 51 consists of a brassière side part 57, a web 59, a web 60 and a strip 54 or 55. The lower end of each web of each side of garment 51 has secured thereto and transversely thereof an elastic strap 63. One of the elastic straps 63, at each side of the garment 51, has one end secured to one side of front portion 61 and its other end to the front side of a strip 54 or 55 and the other elastic strap 63 of each side of

the garment has one end secured to the rear side of a strip 54 or 55 and its other end to one side of the back portion 62. The strip 54 or the strip 55 has secured thereon at its upper end a pair of spaced parallel flexible stays 64 positioned at, extending above and depending from the waist-line of the garment.

The garment 51 includes four sets of elastic members of tape-like form. The said sets are arranged in pairs, that is to say, a front and a rear set indicated at 65, 66 respectively. The front set of a pair is oppositely disposed with respect to the rear set of the pair. The sets of one pair are arranged at one side and the sets of the other pair are arranged at the other side of the garment. Each set consists of three elastic members. The front sets align with each other. The rear sets align with each other. The members of each front set are indicated at 67, 68, 69. The members of each rear set are indicated at 70, 71, 72. The members of the front sets are secured to the inner faces of the upper portions of the webs 59. The members of the rear sets are secured to the inner faces of the upper portions of the webs 60. The ends of the members of the front sets are secured to the sides of the front portion 61 and one side of the strips 54, 55. The ends of the members of the rear sets are secured to the other side of the strips 54, 55 and the sides of the back portion 62. The members of the front sets are arranged in a like manner, that is to say the members 67 of such sets extend forwardly at an upward inclination from the front side of the strips 54, 55 to the sides of the front portion 61; the members 68 of such sets are horizontally disposed and extend forwardly from the front side of the strips 54, 55 to the sides of the front portion 61; and the members 69 of such sets extend forwardly at a downward inclination from the front side of the strips 54, 55 to the sides of the front portion 61. The inclination of the members 69 is greater than the inclination of the members 67. The members 68 are of less length than the members 67, 69. The members 69 are of greater length than the members 67. The members 67, 68, 69 are of uniform width and are secured at their lengthwise edges to the webs 59 by zig-zag stitching 73. The setting up of the members 67 and 69 at an inclination disposed them diagonally with respect to the webs.

The members of the rear sets are arranged in a like manner, that is to say the members 70 of such sets extend rearwardly at an upward inclination from the rear side of the strips 54, 55 to the sides of the back portion 62; the members 71 of such sets are horizontally disposed and extend rearwardly from the rear sides of the strips 54, 55 to the sides of back portion 62; and the members 72 of such sets extend rearwardly at a downward inclination from the rear sides of the strips 54, 55 to the sides of the back portion 62. The inclination of the members 70, 72 is the same, but oppositely disposed. The members 70, 71, 72 are of uniform width. The members 70, 72 are of like length and of greater length than the members 71. The members 70, 71, 72 are secured to the webs 60 by zig-zag stitching 74. The said sets of members are arranged at and above and below the waist-line of the garment 51. The setting up of the members 70, 72 at an inclination dispose them diagonally with respect to the webs. The latter may be provided with hose supporters 75 and is so shown.

The garment 51 functions in the same manner as the garments 10 and 50.

The garment 76 shown by Figures 11 and 12 is of the same construction as the garment 51 with the exception that the number of the elastic members of each set employed in connection with the garment 76 is greater than the number of the elastic members of the sets forming parts of the garment 51. The garment 76 will include a pair of aligned front sets and a pair of aligned rear sets of elastic members. Only one front and one rear set is shown and indicated at 77, 78 respectively. The sets not shown will be arranged on a side of the garment in the same manner as the sets of members which are shown. The front sets and rear sets of elastic members used in connection with the garment 76 will be secured at their ends and lengthwise edges to the body part of the garment 76 in the same manner as the front and rear sets of elastic members 65, 66 respectively are secured to the body part of garment 51. Each front set 77 will consist of four elastic members of tape-like form designated 79, 80, 81, 82. Each rear set 78 will consist of four elastic members of tape-like form indicated at 83, 84, 85, 86. The member 79 is an upper one, the member 82 a lower one and the members 80, 81 a pair of intermediate ones. The member 83 is an upper one, the member 86 a lower one and the members 84, 85 a pair of intermediate ones. The member 79 is of less length than the member 82 and of greater length than the member 80. The latter is of greater length than member 80, but of less length than member 79. The member 83 is of greater length than member 84, but of less length than member 79. The member 84 is of less length than member 80. The member 85 is of greater length than members 83, 84 but of less length than member 79. The member 82 is of greater length than the members 83, 84, 85. The member 86 is of materially greater length than any one of the other members of said sets. The members 79, 80, 81, 82 of said front sets 77 respectively extend forwardly at an upward inclination, forwardly substantially horizontally, forwardly at a downward inclination and forwardly at a downward inclination from the front sides of the strips 87 to the sides of the front portion 88 of the garment. The inclination of the members 79 is greater than the inclination of the members 81 but less than the members 82. The members 83, 84, 85, 86 of said rear sets respectively extend rearwardly at an upward inclination, rearwardly horizontally, rearwardly at a downwardly inclination and rearwardly at a downwardly inclination from the other sides of the strips 85 to the sides of the back portion 89 of the garment. The inclination of the members 83, 85 are substantially the same. The inclination of the member 86 is materially greater than the inclination of the members 83, 85. The setting up of the members 79, 81, 82, 83, 85, 86 at an inclination disposed them diagonally with respect to the webs.

The member 80 is arranged between the members 79, 81. The member 81 is arranged between the members 80, 82. The member 84 is arranged between the members 83, 85. The member 85 is arranged between the members 84, 86. The members 67, 70 extend to the upper ends of the webs 59, 60 respectively. The members 79, 83 extend to the upper ends of the webs 90, 91 respectively.

Otherwise than what is stated in connection

with the garment 76, the latter will be of the same construction as the garment 51.

With reference to the garment 92 shown by Figures 13, 14, it will be of the same structure as the garment 51, with the exception that each of the front sets 93 of elastic members is different from the front sets 65 of garment 51. Each front set 93 will consist of four members 94, 95, 96, 97. The members 94, 97 are the upper and lower members respectively of the set and are disposed at opposite inclinations. The members 95, 96 are the intermediate members of the set. The member 95 is disposed horizontally and the member 96 at a downward inclination. Otherwise than as stated the garment 92 will be of the same construction as the garment 51.

The construction of the garments 76, 92 is to provide for additional control for the abdomen which is obtained by the members 82, 97 respectively. The construction of the garment 92 not only includes the advantage as just stated but further provides to control the buttocks into a flattening position which is obtained by the members 86.

What I claim is:

1. In a garment for women's wear a body structure of girdle-like form including a pair of oppositely disposed elastic webs, non-elastic front and back parts connecting the ends of one web to the ends of the other and oppositely disposed sets of elastic members of tape-like form secured to and extending circumferentially of each of the webs, said members being disposed between and connected to said front and back pieces.

2. In a garment for women's wear a body structure of girdle-like form including a pair of oppositely disposed elastic webs, non-elastic front and back parts connecting the ends of one web to the ends of the other and sets of elastic members of tape-like form secured to the webs, said members being disposed between and connected to said front and back pieces, the members of each of said sets being disposed in spaced relation and extending in different directions, said sets being arranged in pairs, the members of the sets of each pair of sets being oppositely disposed, and a stay means secured to each of said webs and arranged between the sets of a pair of sets.

3. In a garment for women's wear a body structure of girdle-like form including a pair of oppositely disposed elastic webs, non-elastic front and back parts connecting the ends of one web to the ends of the other and oppositely disposed sets of elastic members of tape-like form secured to and extending circumferentially of each of the webs, said members being disposed between and connected to said front and back pieces, and said members arranged against spaced portions of the inner faces of said webs and being secured at their lengthwise edges to the webs by zig-zag stitching.

4. In a garment for women's wear a body structure of girdle-like form including a pair of oppositely disposed elastic webs, non-elastic front and back parts connecting the ends of one web to the ends of the other and sets of elastic members of tape-like form secured to the webs, said members being disposed between and connected to said front and back pieces, said members arranged against spaced portions of the inner faces of said webs and being secured at their lengthwise edges to the webs by zig-zag stitching, said members being disposed against the upper por-

tion of said webs, each of said sets including a horizontal member and a pair of members disposed at opposite inclinations with respect to each other and with respect to said horizontal member.

5. In a garment for women's wear a body structure of girdle-like form including a pair of oppositely disposed elastic webs, non-elastic front and back parts connecting the ends of one web to the ends of the other and oppositely disposed sets of elastic members of tape-like form secured to and extending circumferentially of each of the webs, said members being disposed between and connected to said front and back pieces, said members being disposed against the inner face of the upper portion of said web, each of said sets including a horizontal member, an upwardly inclined member and a downwardly inclined member.

6. In a garment for women's wear a body structure of girdle-like form including a pair of oppositely disposed elastic webs, and spaced sets of spaced elastic combined fashioning and resistance increasing members secured to one of the faces of said webs, said body including a pair of non-elastic front and back parts connecting the ends of one web to the ends of the other web and to which said members are connected, and said body including concealed stay means carried by said webs, intermediate the ends of the latter and to which said members are connected.

7. In a garment for women's wear a body structure of girdle-like form including a pair of oppositely disposed fashioned elastic webs, and spaced sets of spaced elastic combined fashioning and resistance increasing members secured to the inner faces of said webs, said body including a pair of non-elastic front and back parts connecting the ends of one web to the ends of the other web and to which said members are connected, said body including concealed stay means carried by said webs, intermediate the ends of the latter and to which said members are connected, and said body including upper and lower elastic straps secured to the lengthwise edges of said webs and having their ends secured to said front and back pieces.

8. In a garment for women's wear a body structure of girdle-like form including a pair of oppositely disposed fashioned elastic webs, and spaced sets of spaced elastic combined fashioning and resistance increasing members secured to the inner faces of said webs, said body including a pair of non-elastic front and back parts connecting the ends of one web to the ends of the other web and to which said members are connected, said body including concealed stay means carried by said webs, intermediate the ends of the latter and to which said members are connected, and said body including upper and lower elastic straps secured to the lengthwise edges of said webs and having their ends secured to said front and back pieces, each of said members being of like form, and zig-zag stitching for securing the lengthwise edges of said members to said webs.

9. In a garment for women's wear, a body structure of girdle-like form including a pair of oppositely disposed fashioned elastic webs, each having its end terminal portions extended inwardly with respect to its central portion, a stay means disposed at the transverse center of the upper portion of each web, a non-elastic front part interposed between, secured to and for con-

- necting the front ends of the webs together, a non-elastic split back part interposed between, secured to and for connecting the rear ends of the webs together, spaced elastic combined fash-
5 ioning and resistance increasing means carried by the upper portions of the webs and extending from said stay means to the sides of said front and back parts.
10. In a body confining garment, a body struc-
ture for encompassing the wearer and having elastic sides, two pairs of sets of elastic members, each pair of sets being secured to one of the elastic sides of said structure above the lower end of the latter, the sets of each pair extending in
15 opposite directions across a side of said structure, certain of the elastic members of each set being oppositely inclined, said structure including a front portion and a back portion, the front ends of one of the sets of each pair of sets being secured to the sides of said front portion, and the rear ends of the other set of each of said parts of sets being secured to the sides of said back portion.
11. In a foundation type garment having a 5 front, a back, and a pair of sides, and two pairs of oppositely disposed sets of elastic strips, each set including horizontally and diagonally disposed elastic strips, said pairs of sets of strips being secured directly to said elastic sides at points 10 spaced from the top and bottom of said sides, and exerting a control on the stretch of said sides within predetermined areas of the garment, one end of a set of strips of each pair of sets of strips being connected to the side edges of the front 15 and one end of the other set of strips of each pair of sets of strips being connected to the back of the garment.

PHILIP H. ROBBINS.
